(57) **CLAIM**

The ornamental design for a sunrise solar light, as shown and described.

DESCRIPTION

FIG. 1 is a perspective view of a sunrise solar light in accordance with my invention;

FIG. 2 is a side view of the sunrise solar light shown in FIG. 1;

FIG. 3 is a top view of the sunrise solar light shown in FIG. 1; and,

FIG. 4 is a bottom view of the sunrise solar light shown in FIG. 1.

The broken lines shown on the drawing are for illustrative purposes only and form no part of the claimed design.
